(57) **CLAIM**

The ornamental design for an electrical connector housing, as shown and described.

DESCRIPTION

FIG. 1 is a front perspective view of an electrical connector housing showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof, left side elevational view being a mirror image thereof; and,

FIG. 7 is a front perspective view thereof.
